CLAIM

The ornamental design for a soot shield for attachment to a vacuum, substantially as shown and described.

DESCRIPTION

FIG. 1 is a top plan view of a soot shield for attachment to a vacuum, showing my new design;

FIG. 2 is a bottom plan view thereof;

FIG. 3 is a side elevational view thereof;

FIG. 4 is an elevational view of the opposite side thereof;

FIG. 5 is an end elevational view thereof;

FIG. 6 is an elevational view of the opposite end thereof.
